LUBRICATOR

Application filed August 15, 1930. Serial No. 475,523.

This invention relates to lubricators, particularly lubricators of the force feed type, and embodies improvements over the apparatus disclosed in our co-pending application Serial No. 304,862, filed September 10, 1928.

The object of the invention is to provide a mechanical force feed lubricator having means whereby the quantity of lubricant fed may be determined in proportion to the amount consumed as reflected by the pressure against which the lubricant is so fed.

The invention contemplates a mechanical force feed lubricator having a forcing cylinder and a forcing piston operating therein, and a plunger cooperating with the piston and movable in response to an operating member, preferably a cam, to which rotation may be imparted by a moving part of the machine to be lubricated, and a control cylinder and piston connected with the forcing cylinder, the control piston being capable of automatic adjustment in response to variations in pressure of the lubricant fed by the forcing piston and cooperating with means, preferably a lever, which will limit the return stroke of the forcing piston in such a manner that as the pressure of lubricant fed decreases the stroke of the forcing piston may be lengthened to force more lubricant. The particular improvements forming the subject of the present invention are in mechanism associated with the control piston and lever whereby exactness of adjustment and perfection of operation may be obtained and the mechanism simplified, and in means for providing for operation of all or certain of the forcing pistons to produce feed of lubricant at a fixed predetermined rate or quantity, as we will proceed now to explain and finally claim.

In the accompanying drawings illustrating the invention, in the several figures of which like parts are similarly designated, Figure 1 is a transverse sectional elevation of a lubricator of the multiple feed type, the section being taken substantially through a set of elements of one feed mechanism or feed unit. Fig. 2 is a sectional elevation taken substantially on the line 2-2 of Fig. 1. Fig. 3 is a fragmentary section similar to Fig. 1

but illustrating a modification. Fig. 4 is a fragmentary sectional plan view taken on line 4-4 of Fig. 2. Fig. 5 is a sectional end view of the lubricator illustrating a means capable of substitution for the control cylinder whereby the feed of lubricant may be maintained at a fixed predetermined rate or quantity. Fig. 6 is a fragmentary sectional view illustrating the means for and manner of adjusting the cam shaft.

The lubricator has a body 1 which provides a reservoir for lubricant, this body being provided with a filling opening 2 having a strainer 3 and a removable filler cap 4. Suitable lugs 5 and studs 6 may be provided for attaching the lubricator to and supporting it upon a suitable supporting member.

Extending substantially centrally through the lubricator body from end to end is a shaft 7 having a bearing 8 in one end of the casing, the opposite end of the shaft having a bearing 9 in the spindle 10 of a spider 11. This spider 11 carries drive pawls 12 which cooperate with a ratchet wheel 13 carried by the shaft 7. A similar ratchet wheel 14 adjacent to the bearing 8 of the shaft is engaged by drag pawls 15. The outer end of the spindle 10 (see Fig. 2) extends through a stuffing box 16 outside of the casing 1, and is provided with a suitable driving member 17 adapted to be connected with a reciprocating element and by means of which an intermittent or step-by-step rotation may be imparted through the drive pawls 12 and ratchet wheel 13 to the shaft 7. Obviously, the shaft 7 may be otherwise intermittently or continuously rotated.

Suitably arranged in and carried by a removable member 18 which forms a bottom for the casing 1, (see Fig. 1), is a plurality of longitudinally aligned forcing cylinder members 19 provided with strainer screens 20 which protect the lubricant inlet passages 21 of the cylinders against entrance of foreign matter. In each cylinder 19 is a forcing piston 22 provided with an expandible packing member 23 at its bottom and with a head 24 at its top. Between a suitable shoulder 25 on the cylinder member 19 and the

head 24 is arranged a spring 26 tending normally to force the piston out of the cylinder, or in other words, to impart a return stroke to the piston. The forcing pistons are 5 interiorly bored upon two diameters to form, respectively, a bore for the reception of a forcing plunger 27 and a lubricant inlet opening 28. A lateral bore 29 communicates with the interior bores and is adapted upon 10 register with the inlet ports 21 to admit lubricant through the bore 28 into the forcing cylinder. In vertical alinement with each of the forcing plungers 27 is a cam or eccentric 30 keyed to the shaft 7 and rotatable therewith. These eccentrics, as shown, 15 may be set at various angles relatively to the shaft, so that the several forcing plungers may be and preferably are successively rather than simultaneously operated. The 20 forcing plungers 27 are held in contact contact with their respective cams 30 by means of springs 31 confined between the heads 32 of the plungers and the heads 24 of the forcing pistons.

25 Each of the forcing cylinders communicates through passages 33 and 34 provided with check valves 35 and 36, respectively, with a bore 37 leading into a control cylinder 38 provided with a control piston 39 having a head 40. In vertical axial alinement with each of the control pistons 39 is a presser foot 41 having a shank 42 slideable within a sleeve member 43 and backed up by a spring 44, the normal tendency of which spring is 30 to force the presser foot downwardly toward the control piston 39. These parts 41, 42, 43 and 44 provide a spring-pressed member and an abutment for the spring thereof. Each 35 of the sleeve members 43 extends upwardly through a guide member 45 and is provided for a considerable distance adjacent to its upper end with screwthreads 46 cooperating with complementary screwthreads in the upper longitudinally extending bracket member 47 preferably integral with and carrying the several guides 45. Above its screwthreaded portion 46 each sleeve member 43 is provided with a non-cylindrical extension or end 48, 40 preferably octagonal, and arranged for cooperation with all of these octagonal ends is a locking bar or wrench 49 having a number of octagonal sockets 50 equal in number to the number of sleeve members 43. The locking bar or wrench 49 is also provided with 45 a socket wrench end, the socket 51 of which is complementary to the octagonal ends 48 of the several sleeve members 43, whereby upon removal of the locking bar or wrench from the position shown in Fig. 4, it may be used 50 to adjust any one or all of the several sleeve members, as may be necessary or desired.

The shanks 42 of the presser feet are provided with rods 52 which extend upwardly through the sleeve members 43 and above the octagonal portions thereof, the upwardly

projecting ends of the rods being provided with screwthreads 53 for a purpose hereinafter explained.

The bracket member 47 is provided with a gage member 54 (see Figs. 1, 2 and 4) which furnishes a means whereby the relative vertical adjustment of the several sleeve members may be gaged by means of a suitable rule, as will be hereinafter explained.

The parts last described, including the upper ends of the sleeve members 43, the bracket member 47, locking bar or wrench 49, etc., are housed within a removable cover or cap 55 mounted upon studs 56 and held in place by nuts 57.

Extending between the head 40 of each of the control pistons 39 and its respective axially alined presser foot 41 is one end 58 of a lever 59 pivoted at 60 upon a bracket 61 carried by the part 18. The opposite end 62 of this lever is forked and embraces its respective forcing plunger 27 and thus extends into the path of movement of and is in position to limit upward or return movement of the respective forcing piston 22. Obviously, the lower the end 58 of the lever 59 descends, the higher its opposite end 62 will lie above its respective forcing piston, and hence the longer will be the return stroke of the forcing piston and the greater the amount of lubricant which may be displaced by it upon its forcing stroke under the influence of its cam 30. Under no circumstances can the adjustment of the end 62 of lever 59 relatively to its forcing piston be such that the forcing piston can follow its forcing plunger completely upward. The reason for this is that the end 63 of the forcing plunger is formed as a valve for cooperation with the upper end of the bore 28. Hence, in order to admit oil through the openings 21, ports 29 and bore 28 to the forcing cylinder, the end 63 of the forcing plunger 27 must rise sufficiently higher than the forcing piston to unseat its end 63 from the bore 28. When the forcing plunger makes its downward stroke its end 63 seats in bore 28, and closes this bore and hence seals the forcing cylinder, and carries the forcing piston downwardly into the cylinder, thus forcing the lubricant through the bores 33 and 34 past check valves 35 and 36 and into the feed pipe 64, there being one of such feed pipes for each feed unit. Continued operation of the lubricator will build up pressure in the feed pipes 64 and this pressure will, through the bores 37, be communicated to the control cylinders 38 and the control pistons 39 therein. As the pressure thus built up rises, it will raise the control piston and with it the end 58 of lever 59 until the presser foot 41 seats against the end of sleeve member 43, as shown in Fig. 1, and thus the end 62 of lever 59 will be depressed to its limit to permit only the minimum stroke of the forcing piston and consequently the min-

100

130

imum feed of lubricant. If the pressure of lubricant upon the control piston 39 decreases, for any reason, the control piston will lower, and the end 58 of lever 59 will 5 follow the control piston under the influence of the spring 44 and presser foot 41, and the end 62 of lever 59 will be elevated to permit increase of the forcing stroke of the forcing piston. As the pressure again builds up the 10 original rate of feed will be reestablished.

Lubricators of this type, when they leave the factory and are delivered to the user, have their forcing pistons so adjusted as to have a stroke of approximately one-sixteenth 15 of an inch. This length of stroke has been found to be fully effective for the purposes for which the lubricator is primarily designed. If, however, it should be found necessary to increase or diminish this stroke, 20 this may be done as follows:—First the cap 55 is removed, by removing the nuts 57. Then the wrench 49, which is usually sealed in position when the lubricator leaves the factory, is removed by breaking the seal and 25 lifting it off of the octagonal ends 48 of the sleeve members 43. Then the socket end 51 of the wrench is applied to the octagonal end 48 of that sleeve member which forms a part of the forcing unit the feed of which is 30 to be increased or diminished.

One full turn downward of a sleeve member 43 will approximately double the feed of lubricant produced by the forcing piston associated therewith. Thus a one-eighth turn 35 or rotation of the sleeve member, which rotation can be accurately observed, will substantially increase the feed to that particular unit. The effect of so turning the sleeve member 43 as to lower it will result in the 40 earlier stopping the rise of the end 58 of lever 59 and less depression of the end 62 thereof, thus permitting increased stroke of its respective forcing piston. Similarly, turning 45 of the sleeve member in the opposite direction will permit greater rise of the end 58 of the lever under influence of its respective control piston 39 and consequently greater depression of its end 62 and shortening of the forcing stroke of the forcing piston.

Obviously, the several sleeve members and consequently the forcing effect of their respective forcing units, may be adjusted independently in this manner, and after desired adjustment has been made, such adjustment 50 may be retained by replacement of the wrench 49, as shown in Fig. 4.

If an undesired difference in feed between certain of the forcing units is noticed, those units may be checked by placing a suitable scale with its end resting against the top of the sleeve member 43 and sighting on the scale against the gage member 54. By thus sighting all of the several sleeve members and adjusting them appropriately to bring 55 them all to the same reading on the scale with

respect to the gage member 54, the feeds of the several units may be equalized. This is true for the reason that all of the sleeve members and the control parts associated therewith are substantially identical and standard, and any difference in the setting of any of the sleeve members will indicate a difference in the stroke of the forcing pistons associated therewith. 70

If it should be desired to remove all of the sleeve members 43 and the parts directly connected therewith as a unit, this may be done readily by disconnecting the bracket member 47 from its supports in the casing 1 by removing the nuts 65 from the studs 56 and lifting the whole assembly bodily out of the casing 1. It will be obvious that when this is done, some means must be provided to hold the presser feet 41 against movement under the influence of their springs 44, otherwise they and the springs would drop into the reservoir. It is for this purpose that we provide the screwthreads 53 at the upper ends 80 of the rods 52, for by applying nuts to these rods by means of these screwthreads, they, 85 and the presser feet 41 and springs 44 with them, may be held against movement relatively to the sleeve members 43 and be thus removed with the other parts. 90

In order to adjust the several pumping units so that their setting may be made uniform, we provide the bores 37 throughout a portion of their length with screwthreads 66 and give access thereto through openings provided with plugs 67, and provide the drag ratchet with a plurality of bores corresponding in number to the number of pumping units, in the instance illustrated six, as indicated at *a*, *b*, *c*, *d*, *e*, and *f*. By reference to Fig. 1, it will be seen that these six bores are 95 in radial alinement with the low points of the six cams 30 indicated at *a'*, *b'*, *c'*, *d'*, *e'* and *f'*, respectively, which cooperate with the pumping units which, for convenience of description we will call Nos. 1, 2, 3, 4, 5 and 6, 100 reading from left to right of Fig. 2. As will be seen by reference to Figs. 1 and 6, the bore *a* which bears a definite relation to the cam *a'* of pumping unit No. 1, passes completely 105 through the ratchet 14 whereas the other bores *b*, *c*, *d*, *e* and *f* pass only part way therethrough. Thus when a rod 14^a is inserted in an opening 14^a, as shown in Fig. 6, it may be 110 passed freely through bore *a*, thus indicating that the cam *a'* of unit No. 1 is in its lowest position, whereas this rod will enter but will be stopped by the other bores which pass only part way through the ratchet. Thus, when bore *a* has been found, the other bores may be located in proper sequence by appropriate 115 counter-clockwise rotation of shaft 7, as viewed in Fig. 1. 120

The desired adjustment of the several pumping units is accomplished by first adjusting each of the pumping units to a posi- 125 130

tion in which there is no movement of its forcing piston 22, called a "no-stroke position". This is done in the following manner:—To set pumping unit No. 1 to no-stroke position, a suitable plug (not shown) is removed from the opening 14^a and the rod 14^b is passed through this opening until it strikes against the ratchet 14. The ratchet 14 is then rotated by means of shaft 7 until the rod passes through bore *a*. It will thus be apparent that cam *a'* is so positioned that forcing piston 22 of No. 1 unit is in its lowest position. Obviously, others of the bores *b*, *c*, *d*, etc., may be encountered by rod 14^b before bore *a* registers therewith, but due to the fact that the rod will not pass through any of these other bores it will be known that bore *a* has not yet been found.

After cam *a'* has been positioned in this manner, the plug 35' and check valve 35 are removed from unit No. 1 and a rod (not shown) having screwthreads similar to those of plug 35' is screwed into bore 28' until it engages the bottom of piston 22, thus holding the piston 22 and plunger 27 against the cam *a'*. Also the plug 67 is removed, and a screwthreaded rod (not shown) is screwed into bore 37 to force control piston 39 upward against the end 58 of lever 59, the forked end 62 of this lever being thereby forced down against the head 24 of piston 22. Then, a nut is applied to the threaded end 53 of rod 52 to hold the spring 44 compressed and presser foot 41 in contact with the end of sleeve member 43. Then member 43 is screwed down by means of its octagonal end 48 until presser foot 41 strikes the end 58 of the lever. The portion of gage 54 adjacent to this sleeve member is then filed down even with the top of the portion 48. Now, if sleeve member 43 is screwed down so that the top of 48 is one thirty-second of an inch below the top of gage 54, unit No. 1 will have a forcing stroke of one thirty-second of an inch. Thus, when the rods are removed from bores 28' and 66 and the check valve and plugs replaced, unit No. 1 is in condition for operation.

Obviously the other units may be adjusted in like manner by successively engaging the rod 14^a with the bores *b*, *c*, *d*, *e* and *f* in succession, by proper rotation of shaft 7.

Of course the sleeve members 43 are rotated the desired number of turns to give the desired stroke to the forcing pistons 22 and then the wrench 49 is applied to all of the ends 48, as shown in Fig. 4.

In order that the adjustment-retaining function of the wrench 49 may be supplemented to prevent any possible movement of the sleeve members 43 which might take place relatively thereto because of wear or the like, we split the upper portions of the screw-threaded portions of the bracket member 47 longitudinally and provide between each of

such members a locking cap screw 67' by means of which a clamping action between the parts may be obtained. Obviously, when adjustment is to be made, these cap screws must be loosened and then tightened after adjustment is completed.

Under some conditions it may be deemed advisable to adjust all of the forcing units to full forcing stroke and effect preferably from remote control, for example, from the cab of a locomotive to which the lubricator may be applied, and we have devised the means illustrated in Fig. 3 for this purpose.

These means comprise above each of the control assemblies and in axial alignment therewith, a fluid pressure cylinder 68 preferably forming a part of the cover member 55 and provided with a piston 69 having a stem 70 slidable in a guide 70' and provided with an adjustable push rod 70^a extending into proximity to the screwthreaded end of its respective rod 52. Pressure fluid may be admitted above the pressure piston 69 through a duct 71 connected with a supply pipe 72.

It will be seen that when pressure fluid is admitted above the piston 69, the piston will be forced down and its push rod 70^a will contact with and depress the rod 52, thus depressing the presser foot 41 and so oscillating the lever 59 as to increase the stroke of the respective forcing piston. When the pressure is relieved above the piston 69, it will be returned to normal position by a spring 73.

Obviously, all of the pistons 69 may be operated simultaneously or separately as desired by the provision of an appropriate valve control for the pressure fluid feed pipes 72.

In order that the extent of depression of the rod 52 may be adjusted, we provide a screwthreaded plug 74 in a cap 75 which forms the top of the cylinder 68, and this plug may be removed and a socket wrench inserted to loosen the lock-nut 76, after which the push rod 70^a may be adjusted by means of a screwdriver, and the nut 76 thereafter tightened.

It will thus be seen that we provide a lubricator, having the characteristics hereinbefore mentioned, in which the mechanism for effecting control of the lubricant forcing effect of the forcing pistons is simplified and improved as compared with the equivalent mechanism employed in the lubricator disclosed in our co-pending application mentioned.

In the present invention the levers 59 by means of which the return stroke of the several forcing pistons is determined, are actuated directly by the control pistons rather than through intermediate mechanism, as disclosed in the lubricator of said co-pending application, the ends 58 of such levers being maintained in operative position in engagement with the control pistons by means of spring-pressed presser feet 41 and adjustable

members 43 whereby the limits between which the stroke of the several forcing pistons may be varied, is directly determined. Moreover, we provide means whereby all of the spring-pressed members mentioned, specifically the sleeve members 43, may be fixed in adjusted position in such a manner as to preclude the likelihood of their becoming vibrated or otherwise rotated out of adjustment.

10 In some installations it may be found desirable to dispense with the automatic pressure-responsive control of the stroke of the forcing pistons 22, and to maintain a constant adjustment of such stroke, either of one or 15 more of such pistons, or of all of same. To this end we provide the mechanism illustrated in Fig. 5, which may be used to replace the parts of the control arrangement hereinbefore described. This mechanism includes a 20 plug 77 which may be screwed into the bore provided for the control cylinder 38 of Fig. 1, having openings 78 for the reception of a spanner, and provided with an interior, screw-threaded bore 79 within which is adjustably fitted the complementally threaded end of a rod 80. This rod 80 carries a fixed collar 81 with which the forked end 58' of a lever 59' engages, the other forked end 62' of this lever engaging the head 24 of the forcing piston 22. The upper end of the rod 80 is screw-threaded as indicated at 82, and passes through a bracket 47', by which it is guided. Appropriate rotation of the rod 80 by means of its non-cylindrical end 83 results 30 in the raising or lowering of its collar 81 by means of the screwthreaded arrangement at 79. Adjustment, when obtained, may be fixed by means of a lock-nut 84 seating against the top of the bracket 47'. A wrench 85, similar to the wrench 49, may be provided for locking the plurality of rods against rotation.

With this arrangement it will be obvious that the lower the setting of the collar 81 the greater will be the forcing effect of the forcing piston of its respective unit, and the higher the setting of this collar, the less will be such forcing effect. But, so long as the same adjustment is maintained, the stroke of the forcing piston will remain the same, as distinguished from the arrangement previously described wherein the control cylinder and piston arrangement is used.

One of the marked advantages of our lubricator in which the control units are used, both as hereinbefore described and as disclosed by our said co-pending application, is that when the pipes leading from the lubricator to the points of delivery are empty, the forcing pistons will automatically operate at full stroke immediately upon the starting of the operation of the lubricator, and the pipes will be rapidly filled with lubricant. Thus manual adjustment or abnormally rapid initial operation of the lubricator for this purpose, either

by hand or mechanically, is made unnecessary. Of course, as soon as the required predetermined pressure is built up in the pipes the stroke of the forcing pistons is automatically reduced to that necessary to maintain a pressure adequate for normal lubricant feed.

Various changes in details of construction and arrangement of parts of the lubricator, and in its mode of operation, are contemplated as within the spirit of the invention and the scope of the following claims.

What we claim is:—

1. In a lubricator, of the mechanical force feed type, having a lubricant forcing device including a forcing piston, and a control device including a control piston for determining the stroke and hence the forcing effect of said forcing piston, the combination of means operated upon by said control piston for determining the stroke of the forcing piston including a lever pivoted intermediate its ends and having one end resiliently maintained in cooperation with the control piston and its other end extending into the path of movement of said forcing piston.

2. In a lubricator, of the mechanical force feed type, having a lubricant forcing device including a forcing piston, and a control device including a control piston for determining the stroke and hence the forcing effect of said forcing piston, the combination of means operated upon by said control piston for determining the stroke of the forcing piston, including a lever pivoted intermediate its ends and having one end resiliently maintained in cooperation with the control piston and its other end extending into the path of movement of said forcing piston, the means for resiliently maintaining said lever end in cooperation with said control piston including a spring-pressed member bearing against said lever end, and a member forming an abutment for the spring of the spring-pressed member and for said spring-pressed member and adjustable relatively to said lever.

3. In a lubricator, of the mechanical force feed type, having a lubricant forcing device including a forcing piston, and a control device including a control piston for determining the stroke and hence the forcing effect of said forcing piston, the combination of means operated upon by said control piston for determining the stroke of the forcing piston, including a lever pivoted intermediate its ends and having one end resiliently maintained in cooperation with the control piston and its other end extending into the path of movement of said forcing piston, the means for resiliently maintaining said lever end in cooperation with said control piston including a presser foot, an adjustable member by which said presser foot is carried and relatively to which it is movable, and a spring interposed between said presser foot and adjustable member, said adjustable member be-

ing adjustable toward and away from said control piston.

4. In a lubricator, of the mechanical force feed type, having a lubricant forcing device including a forcing piston, and a control device including a control piston for determining the stroke and hence the forcing effect of said forcing piston, the combination of means operated upon by said control piston for determining the stroke of the forcing piston, including a lever pivoted intermediate its ends and having one end resiliently maintained in cooperation with the control piston and its other end extending into the path of movement of said forcing piston, the means for resiliently maintaining said lever end in cooperation with said control piston including a presser foot, an adjustable member by which said presser foot is carried and relatively to which it is movable, a spring interposed between said presser foot and adjustable member and a rod connected with said presser foot and extending through said adjustable member and provided with means whereby relative movement between said presser foot and adjustable member may be prevented, said adjustable member being adjustable toward and away from said control piston.
5. In a lubricator, of the mechanical force feed type, having a plurality of lubricant forcing units each including a forcing piston and a control piston, the combination of means operated upon by the control pistons for determining the forcing effect of the forcing pistons, including a plurality of levers pivoted intermediate their ends and having one end resiliently maintained in cooperation with the control pistons and their other ends in the path of movement of the forcing pistons, the means for resiliently maintaining said lever ends in cooperation with said control pistons including spring-pressed members bearing against said lever ends, and adjustable members forming abutments for the springs of the spring-pressed members, said adjustable members provided with means whereby their adjustment may be fixed relatively to each other.
6. In a lubricator, of the mechanical force feed type, having a plurality of lubricant forcing units each including a forcing piston and a control piston, the combination of means operated upon by the control pistons for determining the forcing effect of the forcing pistons, including a plurality of levers pivoted intermediate their ends and having one end resiliently maintained in cooperation with the control pistons and their other ends in the path of movement of the forcing pistons, the means for resiliently maintaining said lever ends in cooperation with said control pistons including spring-pressed members bearing against said lever ends, and rotatably adjustable members forming abut-

ments for the springs of the spring-pressed members, said adjustable members provided with means whereby their adjustment may be fixed relatively to each other including a locking bar engageable with all of said adjustable members simultaneously.

7. In a lubricator, of the mechanical force feed type, having a plurality of lubricant forcing units each including a forcing piston and a control piston, the combination of means operated upon by the control pistons for determining the forcing effect of the forcing pistons, including a plurality of levers pivoted intermediate their ends and having one end resiliently maintained in cooperation with the control pistons and their other ends in the path of movement of the forcing pistons, the means for resiliently maintaining said lever ends in cooperation with said control pistons including spring-pressed members bearing against said lever ends, and adjustable members forming abutments for the springs of the spring-pressed members, said adjustable members provided with means whereby their adjustment may be fixed relatively to each other including a non-cylindrical exposed end on each of said adjustable members and a locking bar provided with sockets complementary to said ends and engageable with all of said ends simultaneously.

8. In a lubricator, of the mechanical force feed type, having a plurality of lubricant forcing units each including a forcing piston and a control piston, the combination of means operated upon by the control pistons for determining the forcing effect of the forcing pistons, including a plurality of levers pivoted intermediate their ends and having one end resiliently maintained in cooperation with the control pistons and their other ends in the path of movement of the forcing pistons, the means for resiliently maintaining said lever ends in cooperation with said control pistons including spring-pressed members bearing against said lever ends, adjustable members forming abutments for the springs of the spring-pressed members, and a bracket member provided with guides and supporting and adjusting means for said adjustable members, said adjustable members, springs and spring-pressed members being removable with said bracket member from said lubricator as a unit.

9. In a lubricator, of the mechanical force feed type, having a plurality of lubricant forcing units each including a forcing piston and a control piston, the combination of means operated upon by the control pistons for determining the forcing effect of the forcing pistons, including a plurality of levers pivoted intermediate their ends and having one end resiliently maintained in cooperation with the control pistons and their other ends in the path of movement of the forcing pis-

- tons, the means for resiliently maintaining said lever ends in cooperation with said control pistons including spring-pressed members bearing against said lever ends, adjustable members forming abutments for the springs of the spring-pressed members, and a bracket member providing a support and guide for said adjustable members, said bracket member carrying means whereby the 5 adjustment of said adjustable members may be gaged.
10. In a lubricator, of the mechanical force feed type, having a plurality of lubricant forcing units each including a forcing piston and a control piston, the combination of means operated upon by the control pistons for determining the forcing effect of the forcing pistons, including a plurality of levers pivoted intermediate their ends and having one end resiliently maintained in cooperation with the control pistons and their other ends in the path of movement of the forcing pistons, the means for resiliently maintaining said lever ends in cooperation 15 with said control pistons including spring-pressed members bearing against said lever ends, adjustable members forming abutments for the springs of the spring-pressed members, a bracket member providing a support and guides for said adjustable members, and cooperating screwthreads in said bracket member and adjustable members whereby the latter may be adjusted.
- 20 11. In a lubricator of the mechanical force feed type, having a lubricant forcing device including a forcing piston, and a control device, said control device including a control cylinder and piston for automatically determining the stroke of the forcing piston in response to lubricant pressure and means operated upon by said control piston for determining the stroke of the forcing piston including a lever pivoted intermediate its ends and having one end cooperating with the 25 control piston and its other end extending into the path of movement of said forcing piston, of means adapted to replace said control cylinder and piston for rendering said stroke adjustment non-automatic, said means including an adjustable member for cooperation with the first-mentioned end of said lever.
- 30 12. In a lubricator of the mechanical force feed type, having a lubricant forcing device including a forcing piston, and a control device, said control device including a control cylinder and piston for automatically determining the stroke of the forcing piston in response to lubricant pressure and means operated upon by said control piston for determining the stroke of the forcing piston including a lever pivoted intermediate its ends and having one end cooperating with the 35 control piston and its other end extending into the path of movement of said forcing piston, of means adapted to replace said control cylinder and piston for rendering said stroke adjustment non-automatic, said means including a manually adjustable member for cooperation with the first-mentioned end of said lever, and means for fixing said member in adjusted position, whereby the forcing effect of said forcing piston may be maintained constant.
- 40 In testimony whereof we have hereunto set 75 our hands this 12th day of August A. D. 1930, and this 12th day of August, 1930, respectively.
